DESIGN FOR A COMBINED SHOW AND MERCHANDISING CASE

William J. Bovers, Caldwell, N. J., assignor to
F. W. Woolworth Co., New York, N. Y., a corporation of New York

Application July 6, 1944, Serial No. 114,324

Term of patent 14 years

(Cl. D80—11)

To all whom it may concern:

Be it known that I, William John Bovers, a citizen of the United States, residing at Caldwell, in the county of Essex and State of New Jersey, have invented a new, original, and ornamental Design for Combined Show and Merchandising Case, of which the following is a specification, reference being had to the accompanying drawing, forming part thereof.

The figure is a perspective view of a combined show and merchandising case showing my new design.

I claim:

The ornamental design for a combined show and merchandising case, substantially as shown.

WILLIAM J. BOVERS.
